UNITED STATES PATENT OFFICE

146,165

DESIGN FOR A SPOON OR SIMILAR ARTICLE

Allan Adler, Burbank, Calif.

Application April 29, 1946, Serial No. 129,122

Term of patent 14 years

(Cl. D54—12)

To all whom it may concern:

Be it known that I, Allan Adler, a citizen of the United States, residing at Burbank, in the county of Los Angeles and State of California, have invented a new, original, and ornamental Design for Spoon or Similar Article, of which the following is a specification, reference being had to the accompanying drawing, forming part thereof.

Fig. 1 is a top plan view of a spoon or similar article showing my new design.

Fig. 2 is a side view.

Fig. 3 is a rear plan view.

Fig. 4 is an end view.

The salient features of my design are shown in full lines.

I claim:

The ornamental design for a spoon or similar article, substantially as shown and described.

ALLAN ADLER.
